(57) **CLAIM**

The ornamental design for a cabin seat, as shown and described.

DESCRIPTION

FIG. 1 is a front perspective view of the cabin seat showing our new design;

FIG. 2 is a rear perspective view of the cabin seat of FIG. 1;

FIG. 3 is a front view of the cabin seat of FIG. 1;

FIG. 4 is a rear view of the cabin seat of FIG. 1;

FIG. 5 is a left side view of the cabin seat of FIG. 1;

FIG. 6 is a right side view of the cabin seat of FIG. 1;

FIG. 7 is a top view of the cabin seat of FIG. 1; and,

FIG. 8 is a bottom view of the cabin seat of FIG. 1.

In FIGS. 1-8, broken lines below the cabin seat indicate environmental structure that forms no part of the claimed design. The broken lines shown on the headrest and inner seat portion of the cabin set represent stitching.
